CASING FOR TRUCK AND FREIGHT
CAR HEATERS

Peter A. Anderson, Portland, Eric Martin Anderson, Sr., Westbrook, Earl W. Hansen, Bangor, and John H. Edwards, Portland, Maine, assignors to Utilities Distributors, Inc., Portland, Maine, a corporation of Maine

Application April 30, 1943, Serial No. 485,226

4 Claims. (Cl. 220—55)

1

The present invention relates to improvements in casing for truck and freight car heaters, and has for an object to provide an improved heater for portable use in trucks, freight cars and the like, to keep perishables from freezing.

Another object of the invention is to provide such a heater constructed and built into a protection screen which extends wholly about the heater and is equipped with disappearing handles for carrying the same.

A further object of the invention is to provide an improved heater of this character which will require no attention in firing and which will maintain the automatic heat control to a very close degree setting and will automatically shut off should the pilot be extinguished.

Further objects of the invention are to provide safety to the operator and others in or about the heater in that the heater will not give off carbon monoxide gas; the same operates on a service and reserve fuel supply; admits servicing without interruption of heat; is constructed of relatively light weight, provides for long hours of continuous operation, is compact, rigid in construction, economical of fuel consumption and admits of quantity manufacture.

With the foregoing and other objects in view, the invention will be more fully described herein-after, and will be more particularly pointed out in the claims appended hereto.

In the drawings, wherein like symbols refer to like or corresponding parts throughout the several views,

Figure 1 is a perspective view of an improved truck and freight car heater, with parts broken away and parts shown in section, as constructed in accordance with the present invention.

Figure 2 is a central vertical cross section of the casing and screen.

Referring more particularly to the drawings 10 and 11 indicate two cylinders or bottles of the gas fuel, which are connected, in a well known manner, to an automatic equipment serving gauge 12. This gauge is connected by a line 54 to the burner 14, which is protected by the pilot 15 and the temperature regulator or thermostatic 16.

Gas is drawn from one container until it becomes exhausted; whereupon the regulator 12 automatically shifts to the second container, and the indicating gauge 17 indicates that gas is being drawn from the reserve supply. A metal disc 18 extends beneath the burner 14 and acts in a dual capacity, namely, as a protection to the apparatus below the disc from the heat of the flame and

in the second place as a reflector to cause the heat to spread horizontally outward in all radial directions and upwardly. In this last function the disc 18 cooperates with an inverted cone 19 which constitutes a spreader, serving to spread the flame and heat, and consequently creates more radiation and circulation of heat. The burner 14 is confined between the disc 18 and the cone 19 and the parts 18 and 19 serve to cooperate to divert the heat upwardly and outwardly in all radial directions. The cylinders or containers 10 are held in place by a rod 20 and a bar 21. The lower end of the rod 20 is formed into, or carries, a hook 22, the open end or bill of which extends upwardly in substantial parallelism with the axis of the rod 20. The construction and relation of this bill 22 to the rod 20 is such that, in the tilting position of the rod 20, the bill 22 may engage with a perforation 23 in a base sill 24 which is preferably of metal mounted with its stronger edgewise dimension vertically and rigidly in the bottom portion of the screen frame which contains the burner and its supply equipment. The base sill is welded, brazed, soldered or otherwise affixed to the bottom or floor 29. The upper end portion of the rod 20 is threaded as indicated at 25 to receive a butterfly or other nut 26 which may be readily turned by the fingers of the operator in order to either tighten or loosen the transverse locking bar 21 which bridges across between the two containers 10 and 11 and is notched at each end portion as indicated at 27 in order to cooperate with the rims 28 of the containers. The bar 21 is preferably of an inverted V-construction in cross section with its lower spread legs engaging spaced points on the rims 28.

The containers 10 and 11 are supported upon the bottom or floor 29 of a screen frame or cage which acts as a protection for the equipment. The back 30, sides 31 and 32 and front panel 33 are all of screen or open work mesh construction; being secured together and closed at their upper ends by a preferably imperforate top 34. Handles 35 mounted upon the case enable the entire unit to be lifted as a whole and easily transported to the place of use. The vertical arms of the handles may be slidably mounted in the case so that, when released, the handles will drop down by gravity and lie flush with top edge of frame.

The front panel 33 may be made in any suitable manner for instance of the mesh wire secured to lower and upper style bars 36 and 37 and vertical side bars 38 and 39 all united into

a substantially rectangular open frame to which the mesh 33 is secured. The rear panel 30 and the side panels 31 and 32 may be likewise separately made and welded to the other screen panel members and to the bottom 29 and top 34 in order to unit into an enclosing case of a size suitable for accommodating the containers 10 and 11 and the other equipment as shown.

The front panel 33 is not secured to the case but is readily removable for servicing and replacements. The containers 10 and 11 are of course also removable when empty for substitution by other replenished containers.

The front panel 23 is held in place by a hasp bar 40 and by the use of a padlock 41 which is interlocked in an eye 42 on the outer end of a bolt 43 which is screw threaded or otherwise secured in the top 34, as more particularly seen in Figure 2. The eye 42 is enlarged over the diameter of the shank of the bolt 43 and the upper style bar 37 is provided with the slot 44 to freely slip over the eye 42. In like manner a slot 45 in the upper end of the hasp bar 40 slides freely on and off the eye 42. The slotted portion 45 at the upper end of the hasp bar 40 is offset outwardly from the main vertical plane of the hasp bar 40 in order to allow the major length of the hasp bar 40 to lie close along in front of the screen 33. The upper end, as shown in Figure 2, is turned horizontally outward and then upwardly to extend beneath and in front of the style bar 37.

This position of the main body of the hasp bar 40 brings its lower end into position to pass down into a socket 46 in the central portion of the lower style bar 36 of the front panel. The base sill 24 is long enough to project at its forward end into this socket 46. The projecting end is formed with a notch 47 in vertical registry with the hasp bar 40 to provide a seat in which the lower end of the hasp bar rests in an interlocking engagement with the base sill 24.

By this construction the hasp bar 40 performs a double function in that it interlocks at both upper and lower ends. When the padlock 41 is removed by the use of a key in the possession of an authorized person, the hasp bar 40 is free to be swung or sprung outwardly at its upper end to disengage such end from the eye 42. In this position the hasp bar 40 is free to be lifted to disengage its lower end from the notch 47. This lifting movement of the hasp bar 40 is facilitated by the offset 48.

Whereas the containers 10, 11 and the regulating equipment 12 are mounted below the top 34, the burner, pilot 15 and the thermostat 16 all project above the top 34 and may be supported thereby. These last mentioned parts are also preferably encased in a screen cage comprising the front wall 49, back wall 50 and the sides 51 and 52, all built up of open rectangular frames and secured to one another and erected upon the top 34 and secured thereto in any desirable way. The top 34 serves as a bottom for this superstructure, the top of which may be left open if desired.

In the use of the device, the improved heater requires no attention in firing. The pilot 15 will ignite the main burner 14 whenever the thermostat 16 dictates. This thermostat 16 may be adjusted to a very close degree setting. If the pilot should for any reason become extinguished the supply of the gas is automatically shut off. The burner does not give off carbon monoxide gas

and it is therefore not harmful to the operator or other persons in the truck, car or room.

As soon as one of the containers is exhausted, the companion container is cut in so that the device provides service and reserve fuel supplies.

By removing the pad lock 48, the hasp bar 40 and the front panel 33 may be removed to give complete access to the equipment, thus enabling an exhausted container to be removed without interrupting the service of heat maintained by the reserve container. By loosening the butterfly nut 26 the bar 21 may be disengaged from the rim 23 of an exhausted cylinder and that cylinder may be removed and replaced by a full cylinder; whereupon the notches 27 of the bar 21 are reengaged with the flange 28, and the butterfly nut 26 tightened down in place.

A satisfactory form of the invention has been built to a weight of only 190 lbs., which provides fuel for eighty hours of wide open continuous operation; and perhaps one to two hundred hours normal operation. The overall height of this device is 37 1/4 inches; overall width of 26 1/2 inches and overall depth of 12 3/4 inches; thus making a compact and efficient burner and supply construction. The device can be manufactured in any quantity since the special parts necessary do not require special stamping tools. The parts are rigid in construction being all welded of heavy angle iron frame construction.

The cylinders 10 and 11 may be equipped with excess flow valves which will shut off the supply in case the pigtails 53 are broken or severed.

The improved device is economical of fuel. The transportation of the requisite fuel occupies less space and is easier to handle than fuels presently used for the same purpose. The device is a safeguard against fire in case of accident since it does not utilize solid or liquid fuels.

It is obvious that various changes and modifications may be made in the details of construction and design of the above specifically described embodiment of this invention without departing from the spirit thereof, such changes and modifications being restricted only by the scope of the following claims:

What is claimed is:

1. For use with a pair of supply and reserve gas containers, a casing for receiving same, a removable vertical panel for the casing through which the containers may be introduced and removed and having a socket in an intermediate lower part, a fixed base sill in the casing between the containers with a forwardly-extending notched end removably received into said socket, a bar positioned and constructed to hold the containers down in the casing, a tie-member connecting said bar and base sill, a hasp bar for said removable panel having an end removably received into said socket and the notch of the base sill, and locking means carried on the casing and engaging said hasp bar to prevent said end of the hasp bar from being removed from said socket and notch.

2. For use with twin supply and reserve gas containers, a casing having compartments to receive the containers, a fixed base sill in the casing separating the containers and having a forwardly projecting end with a notch in its upper edge, a removable vertical panel for the casing through which the containers may be introduced and removed and having a socket in a central lower portion opening inwardly and upwardly and adapted to receive the forward notched end

of the base sill, a hasp bar for the panel having a lower end removably fitted through the upper opening of said socket and into said notch, locking means carried by the casing and engaging an upper part of the hasp bar to prevent the lower end from being lifted out of said socket and notch a hold-down bar positioned and constructed to hold the containers down in the casing, and means connecting said bar and base sill.

3. The combination of claim 2 further characterized by the fact that a shoulder on the upper portion of the hasp bar encounters a part of the

panel to prevent lifting of the hasp bar out of the notch of the base sill.

4. The combination of claim 2 wherein an outwardly offset upper part of the hasp bar engages an upper style of the panel to prevent raising the hasp bar, said locking means having a part affixed to the casing and adapted to receive thereon the upper portions of the panel and hasp bar.
